UNITED STATES PATENT OFFICE.

ARTHUR S. RICHARDSON, OF READING, MASSACHUSETTS.

WAX-THREAD SEWING-MACHINE.

SPECIFICATION forming part of Letters Patent No. 377,466, dated February 7, 1888.

Application filed March 22, 1887. Serial No. 231,901. (No model.)

To all whom it may concern:

Be it known that I, ARTHUR S. RICHARDSON, of Reading, county of Middlesex, and State of Massachusetts, have invented an Improvement in Wax-Thread Sewing-Machines, of which the following description, in connection with the accompanying drawings, is a specification, like letters on the drawings representing like parts.

10 United States Patent No. 314,478, granted to me March 24, 1885, shows and describes a wax-thread sewing-machine having a standard of small diameter and flattened at its upper end to constitute a narrow support for the material between the edge of the sole and the point where the needle penetrates the sole, so as to be sure to catch the edge of the upper lasted over upon the inner sole.

15 It is a great desideratum to reduce the diameter of the standard as much as possible throughout its entire length, especially all that part of the standard that enters the shoe, so that the shoe may be tipped freely, as is necessary when the stitching is being done about 25 the toe.

20 To do this I have applied my improved standard to a machine wherein the feeding of the shoe is done by an awl located above the post rather than by a needle within the post; 30 and to enable the cast-off to take up the least possible space in the standard, and yet operate unerringly with the needle, I have provided the needle-bar with a longitudinal groove in which runs or moves the cast-off slide composed of a flattened strip of steel, the point of 35 which is offset to come in contact with the shank of the needle at a point immediately above the needle-bar, the cast-off slide being held closely in the groove in the needle-bar by 40 means of the inner wall of the standard, the needle-bar and cast-off within it fitting the standard, the latter guiding each along its entire stroke.

45 To enable the top of the standard to constitute a narrow work-support, the said standard is made open entirely to its top, such construction being necessary to enable both the cast-off and the needle to be retracted entirely within the standard when the awl is moving 50 the shoe along the top of the support for a new stitch, the point of the awl at such time being

extended through the usual outer sole, upper, and inner sole close to the edge of the inner sole and separated from the said edge by only the thickness of one wall of the upper end of 55 the standard. The standard, at a point below its upper end, is slotted for the passage of the screw which holds the needle in the needle-bar and to permit the operator to have access to the said screw to change a needle without 60 removing the needle-bar.

Figure 1, in front elevation, represents a sufficient portion of a wax-thread sewing-machine to enable my improvements to be understood. Fig. 2 is a detail showing, in vertical section, 65 the standard, part of the frame-work, the needle-bar, and the cast-off, the needle being in elevation, the needle-bar being supposed to be descending. Fig. 3 is a section of Fig. 2 in the line x. Fig. 4 is a top or plan view of the 70 standard, Fig. 2; and Fig. 5 is a section of Fig. 1 in the line x'.

75 The bed-plate or base A, the standard A', supporting the usual overhanging arm, in which is located the rotating shaft for operating the awl-bar, the awl-bar B, the awl b, the vibrating awl-carrying frame B², pivoted at B³ upon a stud at the forward part of the overhanging arm, the arm B⁴, forming part of a rock-shaft and connected to the said frame B² 80 by a link, 2, the presser-foot C, the presser-bar C', the thread-carrier bar C², and the thread-carrier 3 are and may be all as usual in wax-thread sewing-machines wherein the material is fed by an awl.

85 The forward part of the frame-work of the machine has secured to it by bolts d a plate, d', or foot, from which rises a slender standard, d², the upper end of which meets the lower side of the presser-foot. This standard, 90 as herein shown, is made tubular from its upper end downward to a point which will be at or below what will constitute the top of the shoe, so as to offer the least possible obstruction to the free movement of the upper outside of the standard while the stitching is taking place about the toe of the shoe, the standard at such time extending into the vamp substantially to its junction with the inner sole.

95 Referring to Fig. 4, it will be seen that the top of the standard, especially that part of it

between the vamp and the needle, is very narrow or thin, such construction permitting the hooked needle n to penetrate the inner sole, upper, and outer sole very close to the edge of 5 the inner sole, such construction being essential in the manufacture of children's or infants' shoes, in order that the upper may be always caught by the needle.

The needle-bar D at its lower end has connected to it by a screw a block, D' , having a 10 projecting finger which at the proper time strikes the blocks d^2 or d^3 , secured to the cast-off bar e , to raise or lower it in order that the cast-off may co-operate in usual manner with 15 the hook of the hooked needle n to form a stitch. This block D' has a pin or stud which receives the lower end of a link, D^2 , (shown by dotted lines, Fig. 1,) the upper end of 20 which link is connected to a pin or stud of an arm of a rock-shaft, D^3 , which derives its movement from the rotating shaft in the overhanging arm referred to through a link (shown by dotted lines) connected to an arm, D^4 , (shown by dotted lines, Fig. 1,) of the rock- 25 shaft D^3 , the said devices for moving the needle and cast-off bars being substantially the same as now employed in other wax-thread sewing-machines.

The needle-bar D is fitted snugly into and 30 is guided by the standard, as herein shown, to a point above the highest position attained by the needle-bar, the said standard being slotted, as represented at f , Fig. 2, the said slot permitting the needle-holding screw f' to 35 slide up and down the slide, also enabling the operator to gain access to the said screw when it is desired for any purpose to change or adjust the needle, the slot obviating the removal of the needle-bar.

40 The needle-bar throughout the length of the standard is provided with a groove, as shown best in Figs. 2 and 3, which receives in it the cast-off g , herein shown as a thin plate of steel, the upper end of which is offset (see Fig. 2) or 45 bent toward and so as to come in contact with the needle n , the inturned portion of the cast-off in contact with the needle being grooved to partially embrace the needle.

The cast-off from the point 8 to its upper end 50 substantially fills the groove in the needle-bar, the outer edge of the cast-off coming in contact with the inner wall of the standard, so that the cast-off in its reciprocations is held

firmly in place in the groove in the needle-bar.

Referring to Fig. 2, it will be noticed that the standard is open entirely to its top, the hole at the top being of such size as to permit both the cast-off and the needle to be entirely retracted within and below the upper end of the 60 standard, so that the inner sole of a shoe resting upon the top of the standard may be readily moved thereon by the awl, the point of which at such time enters the open upper end of the standard. 65

The standard is herein shown as tubular, as thereby greatest strength and stiffness are attained with a given quantity of metal, the upper end of the standard, however, presenting an oval rather than circular shape, leaving a 70 comparatively narrow slot in the top of the standard in which the awl may move laterally.

I do not broadly claim a base or standard to enter a shoe and support it while being stitched. 75

I claim—

1. In a wax-thread sewing-machine, the slender standard d^2 , open at its upper end, the needle and cast-off bars fitting closely within the said standard, the cast-off entering a groove 80 in the needle-bar, the back of the said cast-off being in contact with the inner wall of the standard to retain the former in the groove of the said bar and both the needle and cast-off being adapted to be retracted entirely within 85 the standard, combined with a presser-foot, an awl, an awl-carrying bar, and means to move the awl-carrying bar to effect the movement of the shoe over the top of the standard, substantially as described. 90

2. The slender work-supporting standard d^2 , slotted at one side, as at f , a longitudinally-grooved needle-carrying bar, and a cast-off entering the said groove, the assembled needle and cast-off bars fitting the interior of the standard snugly, combined with a needle-holding screw, f' , arranged to move in the slot of the standard, substantially as described. 95

In testimony whereof I have signed my name to this specification in the presence of two subscribing witnesses. 100

ARTHUR S. RICHARDSON.
